WALL CONSTRUCTION

Fred Henry Hedinger, Hampstead, England

Application December 17, 1937, Serial No. 180,350
In Great Britain April 21, 1937

12 Claims. (Cl. 72—41)

The present invention relates to a wall construction and particularly relates to a brick wall construction.

In the present type of wall construction, it is customary to form a double wall of two tiers of bricks which are connected by mortar or suitable cementitious material.

Walls of this character require an inner facing of lath or slats to carry plaster and they also are not particularly weather or watertight and do not have most satisfactory heat, weather and sound insulating properties.

Furthermore, it is necessary for the bricklayer to lay two walls with increased labor cost and considerable consumption of cement and wastage of bricks.

To include various pipes or conduits, whether for gas, water or electricity, it is necessary either to make a special construction or to break the wall in various places to include said pipes or conduits.

It is among the objects of the present invention to provide an improved wall construction and system of bricks for forming the same, in which although the bricks may be inexpensively manufactured with high production, it will be possible to secure a most satisfactory wall construction having excellent heat, weather and sound proofing properties with considerable saving in materials and labor.

Another object is to provide an improved wall construction of the character described and brick elements for forming said wall construction, which will enable better thermal insulation of the building or home, giving a warmer building in winter and a cooler building in summer, and which will include provision for conduits for gas, water, oil and electricity without the need of breaking the wall or without the need of special wall constructions.

Another object is to provide a system of interlocking and self aligning brick constructions for runners, corners, window enclosures, joist receptacles, wall ends and so forth which will be pre-formed to be most satisfactorily utilized upon the job, which may be readily employed by brick layers and which will largely eliminate cutting and wastage.

Other objects will be obvious or will appear during the course of the following specification.

In accomplishing the above objects, it has been found most satisfactory to provide an improved cavity brick construction including or consisting of a plurality of longitudinal or stretcher vertical web elements joined at their peripheries by short transverse vertical web elements. Between adja-

cent pairs of longitudinal or stretcher elements, there will be a number of cavities.

In the preferred cavity brick construction, the ends of the bricks are provided with complementary or interengaging tongue and groove or other keying connections which will assure that the ends of the adjacent bricks in the same course in the wall will closely interfit and interlock with each other with the elimination of air spaces between the ends of the bricks.

At the same time, the edge portions at the ends of the bricks adjacent the front and rear faces thereof are so shaped as to leave the substantial recesses adjacent the front and rear faces of the walls on both sides of where the bricks are inter-fitted together with the result that the cement or mortar will be utilized only along the front and back portions of the bricks.

At the same time, the horizontal courses or layers of bricks are altogether separated from each other by a layer of mortar or cement and the bricks in the different rows are preferably so offset, one from another, that the end vertical transverse webs of the bricks will be positioned centrally of the cavities of the bricks in the horizontal course or layer above or below.

In forming the wall, it is desirable that there be free passage of air through the wall in all directions, both horizontally and vertically through the cavities between the longitudinal or stretcher elements. At the same time, no possible passage should be provided between the ends of the bricks so that a most satisfactory weathertight, heat-tight and sound-tight wall construction is obtained.

The keys or complementary projections and grooves on the ends of the bricks are desirably so constructed that the bricks may be reversed on a vertical axis. At the same time, the top and bottom faces of the bricks in combination with said end faces are so constructed as to prevent reversal of the bricks upon a horizontal axis with the result that one horizontal face of the brick will always be the upper face and the other horizontal face will be the lower face although the ends may be interchanged at will.

It is also desirable to provide an enlargement on the central stretcher element by which the brick may be balanced and which will serve as a handle by which the brick may be grasped by the bricklayer.

To enable construction of corners, window frame receivers, joist receptacles and so forth, special types of bricks are employed including the interengaging or complementary keying ele-

ments which may be utilized to form the wall structure and complete the rows of bricks formed by the standard constructions above stated.

In the drawings which show several of the various possible embodiments which may be made according to the present invention:

Figure 1 is a top perspective view of the standard form of brick.

Figure 2 is a fragmentary top perspective view of the adjacent ends of two bricks with the complementary interlocking portions thereof in engagement.

Figure 3 is a transverse sectional view upon the line 3—3 of Figure 1 upon a slightly enlarged scale.

Figure 4 is a fragmentary top perspective view showing how the bricks of Figures 1 to 3 may be utilized in a wall construction.

Figure 5 is another fragmentary top perspective view of the wall construction showing the brick system at a corner and showing the manner in which the bricks are assembled at such corner.

Figure 6 is a top perspective view of a corner brick or quoin.

Figures 7 to 12 are respectively top perspective views of the brick constructions designed to be utilized in connection with the standard runner bricks of Figures 1 to 3, and the corner bricks of Figure 6; Figure 7 showing a face end brick; Figure 8 being a reveal or window enclosure brick; Figure 9 showing a closer brick; Figure 10 showing a half face end brick; Figure 11 showing an angular squint and Figure 12 showing a half runner brick.

Referring to Figure 1, the brick A, as shown, is preferably molded or formed integrally or in one piece, of clay, cinders or other finely divided material cemented or bonded together, or it may be cast of cement, concrete or other materials.

The brick, as shown in A may be fired, the final dimensions of the bricks, as shown in Figure 1, being uniform so that the bricks may be accurately combined to form a wall construction as diagrammatically indicated in Figures 2 and 4.

The runner brick of Figure 1 is provided with the front and back parallel vertical longitudinal or stretcher web elements 10, the intermediate or middle vertical longitudinal or stretcher web elements 11 and the transverse web members 12 and 13 uniting the ends of said stretcher elements 10 and 11.

Formed between the stretcher elements 10 and 11 and the transverse end members 12 and 13, are two longitudinal cavities 14, which communicate with the cavities of other bricks, as indicated in Figure 4 and form part of a continuous air space which extends laterally and vertically through the entire wall structure.

The webs 12 are provided with the outwardly projecting key or male elements 15 which project beyond the end face 16 of the runner element 11, while the webs 13 are provided with the recessed portions 17 which are recessed below the end face 16 of the runner elements 11.

The upper portions of the webs 12 and 13 are longitudinally recessed, as indicated at 18 and 19 to establish communication between the air spaces of the adjacent bricks through each tier, row, course or layer of bricks.

It will be noted that the projecting keys or male elements 15 alternate and are diagonally opposite in each brick as are also the recessed or female portions 17, the flat end faces 16 con-

nected said projecting portion 15 and said recessed portion 17.

The complementary end faces are composed of the surfaces 15, 16 and 17, and these end faces are designed to engage each other in the manner best shown in Figure 2.

The end faces 20 of the back and front runner elements 10 are set behind the end faces 16 so that when the bricks are interfitted, as indicated in Figures 2, 4 and 5, there will be a recess 21 for the reception of mortar.

By the close interfitting of the complementary keying areas 15, 16 and 17, it is assured that air will not pass vertically or laterally past the end junctions between the bricks, while the recesses 21 between the front and back runner elements 10 will insure sufficient area or space for the reception of mortar or other cementing material, which cementing material should preferably be kept away from the space between the front and back runner or longitudinal stretcher elements 10, as indicated in Figure 4.

The brick, as shown in Figure 1, is reversible upon a vertical axis 22, indicated in the dot and dash lines in Figure 1, but is not designed to be reversible upon a horizontal axis indicated by a dot and dash line 23 in the same figure.

Grooves or recesses 24 which may serve as grouting grooves or mortar frogs are only applied to the top surfaces of the runners 10 of the brick A so that the bricklayer will readily perceive when the proper face of the brick is upright. Of course, other distinguishing marks may be applied and the recesses or grooves 24 then could be applied to both the top and bottom faces of the brick.

The middle runner 11 is preferably provided with enlargements 25 which serve to locate the center of gravity and form a convenient handle or grasp for the bricklayer.

The projections and recesses 15 and 17 might be made of trapezoidal or other shapes, but the curved keying structures 15 and 17 are found to be most suitable since they avoid sharp corners which are liable to fracture.

It will be thus seen that with a brick having the three stretcher or longitudinal structure elements 10 and 11, as shown in Figures 1 to 4, there is provided a wall construction in which the intermediate portions of the ends of each brick will interlock with the adjacent bricks in the same layer or course giving a most satisfactory wall construction of only a single brick in thickness.

The cavities 14 are of such a length and width so that the thickness of the webs 10, 11, 12 and 13 will be about the same and so that distortion or uneven drying or setting will be largely eliminated, as might tend to result if there were dissimilar thicknesses in the brick body.

The intermediate portions 26 of the central web or stretcher element 11 may be made slightly thinner than the outside longitudinal elements 10.

It will be noted by reference to Figures 2 to 4 that air passages are provided through the recesses 18 and 19 and also through the longitudinal cavities 14 even though the cavities 14 on one layer or course are bisected or traversed by the webs 12 and 13 on the next layer or course.

The corner brick or quoin shown separately in Figure 6 and in the wall construction of Figure 5, is designed to cooperate with bricks extending in different directions and particularly at right angles to each other to form a weather tight connection between the ends of the rows 75

of the bricks which will prevent movement of water or air between the bricks transversely of the wall.

The brick, as shown in Figure 6, has the front 5 wall portions or longitudinal vertical runner web elements 27, joining at the corner 28 and it is provided with the intermediate vertical longitudinal webs 29, 30, 31, the web 29 extending in the direction 32 of one section of the wall and the other webs 30 and 31 extending in the other direction 33.

The webs 29 and 30 continue the middle webs or longitudinal stretcher elements 11 of the brick of Figures 1 to 4, while the web 31 continues the 15 rear longitudinal stretcher web element 10 of the runner bricks.

The transverse webs 34 and 35 are also provided, said webs being recessed at their upper portions, as indicated at 36, 37 to cooperate with 20 the passages or recesses 18 and 19 in the runner bricks of Figure 1. The bricks also are provided respectively with the key or male projections 38 and the groove or female recessions 39 which are complementary to and are designed to cooperate with the corresponding elements 15 and 17 25 of the runner bricks in the manner indicated in Figure 5.

The grouting grooves or mortar frogs 40 correspond to the grouting grooves or mortar frogs 30 24 of the runner brick of Figure 1.

It will be noted that the projecting portion 41 of the corner brick of Figure 6 causes the side 42 to have the full width to cooperate with one of the runner bricks A in the direction 33, and 35 at the same time, forms a recess 43, the bottom 44 of which is of sufficient width to cooperate with the end of the runner brick A extending in the direction 32.

At the same time, the cavities 45, 46 will continue the air spaces through the corner of the 40 wall and will communicate with the cavities or air spaces 14 in the brick of Figure 1.

When used in the wall, as shown in Figure 5, there will be spaces formed at 47, 48, 49, 50 and 45 51 to receive mortar along the back and front of the wall with the intermediate portions of the wall being devoid of such mortar and with the intermediate portions of the corner brick of Figure 6 and the runner bricks of Figure 1 being 50 in close interfitting engagement.

It will also be noted from Figure 5 that the successive corner bricks B, B' and B² are turned so that their short sides 52 and their long sides 53 will alternate.

To accommodate angles less than 90°, for example, 30, 45 and 60°, it has been found most satisfactory to utilize a squint construction of the character shown in Figure 11 in which correspondingly functioning elements to those shown 55 in Figure 1 are designated by the same numerals primed.

In this construction two of the webs 54 and 55 are of wedge shape and the brick is angled as indicated at 56 so that its face 57 will cooperate 60 with one course or line of bricks extending in the direction 59, while the other end will cooperate with a course or line of bricks extending in the direction 58. The courses or lines 58 and 59 are at an angle of 30, 45 or 60° to each other or some intermediate angle.

The end face bricks 7 and the reveal bricks 8 are designed to be utilized at a flat wall end or at a place where a window frame is to be received respectively.

75 In Figures 7 and 8, corresponding functioning

parts to those shown in Figure 1 are indicated by the same numerals provided respectively with a superior "2" and with a superior "3".

It will be noted that the webs 61 at the end of the brick of Figure 7 are flat and do not have 5 projections or recesses to key with adjacent bricks.

In the construction of Figure 8, the transverse web 62 is offset in respect to the web 63 so as to leave a recess 64 in which the window frame may 10 be fitted.

In Figure 9, is shown a typical closer brick which may be made up of various sizes to accommodate spaces between the runner bricks of Figure 1, the corner bricks of Figures 6 and 11 15 and the end bricks of Figures 7 and 8.

In Figure 9, corresponding functioning parts are included by the same numerals as in Figure 1, provided however, with a superior "4".

It will be noted that the brick of Figure 9 is 20 devoid of the longitudinal cavities of recesses 14 of Figure 1, but if the closer brick is of sufficient width such cavities may also be provided.

The key and groove elements 15⁴ and 17⁴ are 25 diagonally positioned in respect to each other so that the brick may be reversed readily upon a vertical axis.

In Figures 10 and 12, are shown half bricks which may be utilized where joists or window beam members are to be inserted in the wall. 30

Correspondingly functioning parts of the constructions of Figures 10 and 12 are indicated by the same numerals as Figures 1 and 7, provided, however, with a superior "5" and "6" respectively.

The half brick of Figure 10 has a flat end web 35 61⁵ which is designed to form part of a wall end and not to interengage an adjacent brick while the half brick of Figure 12 is designed to be utilized in the regular course and to engage two adjacent bricks.

The inside walls 65 and 66 of these bricks are 40 of such a thickness as to give sufficient strength to the brick, but at the same time, to permit sufficient space inside of the adjacent brick of standard size, as shown in Figure 1, to permit of 45 the reception of a joist or beam, as may be desired.

A wall made of the brick construction, as shown in Figures 1 to 12, is interlocking and aligning and creeping of the courses, due to uneven vertical joints, is eliminated. 50

The wall constructions, as shown in Figures 4 and 5 may be laid much faster since each brick, as shown in Figures 1, 6, 7, 8, and 11, is equivalent in volume to three or more ordinary bricks. Nevertheless, the laying of the wall constitutes an 55 easy single handed job for the bricklayer.

No cutting is necessary on the job as the bricks may be of suitable sizes and shapes ready to fit any dimension and a double cavity wall is obtained 60 in one operation.

The wall construction is better because of the absolute resistance to weather due to the double cavities, and the unique system of permitting 65 multiple ventilation—vertical, horizontal and diagonal—assuring a dry structure.

Perfect thermal insulation giving warmer houses in winter and cooler houses in summer is obtained and the construction is particularly 70 soundproof.

The wall has an attractive appearance and may be made in a variety of pleasing colors. Every brick is a face brick with no ugly exteriors, and the structure has tremendous strength due 75

to the interlocking of the bricks giving a substantially monolithic structure.

Moreover, the wall construction costs much less because of the saving of the bricklayers' time and the weight of material, the mortar saving being up to 75% and the saving in bricklayers' time being up to 50%.

Although the width and height of the bricks may be widely varied, it has been found most convenient for commercial purposes to vary the height from 2 $\frac{5}{8}$ " to 9". As indicated in Figure 2, the bricks A may have a width 61 of about 9" and the runner bricks of Figure 1, the face end bricks of Figure 7, the reveal bricks of Figure 6, the half brick face ends of Figure 10 and the half brick runners of Figure 12 may be of various lengths, say in sizes of 6, 9, and 12 inches.

The closing bricks may be made in 3" lengths, as indicated by the dimension 68 in Figure 9.

It will be particularly noted that there is no mortar extending through the wall from the front or exterior face of the wall to the back or interior face of the wall and all mortar joints are broken. This will make the wall more watertight since there will be no tendency for the mortar to conduct the moisture through the wall.

The enlargements 25 are particularly helpful to masons, bricklayers and so forth since they enable the bricklayer to most readily locate the center of gravity of the brick and avoid canting of the bricks when used in making a wall.

The present application is a continuation in part of application, Serial No: 136,934, filed April 14, 1937.

It is apparent that the specific illustrations shown above have been given by way of illustration and not by way of limitation and that the structures above described are subject to wide variation and modification without departing from the scope or intent of the invention all of which variations and modifications are to be included within the scope of the present invention.

What is claimed is:

1. A wall construction comprising a plurality of courses of individual bricks having spaced vertical longitudinal stretcher elements at the front and back of the brick united together by mortar over the bottom, top and end surfaces of the stretcher elements only, each brick having three stretcher elements, the outside elements forming the front and back of the brick and the inside element extending midway through the brick, the outside elements being shorter than the inside element and forming a recess for reception of said mortar.

2. A wall construction comprising a plurality of courses of individual bricks, each of said bricks being provided with three spaced vertical longitudinal stretcher elements, the outside elements being somewhat shorter than the inside element and said elements being connected at their ends by transverse webs, said bricks abutting each other at the ends of said inside webs and spaces being left between the ends of the outside webs, said bricks being united together by mortar over the marginal bottom, top and end surfaces of the bricks, said bricks having closely interfitting end surfaces between said marginal portions.

3. A wall construction comprising a plurality of layers of individual bricks, each of said bricks being provided with three spaced vertical longitudinal stretcher elements, the outside elements being somewhat shorter than the inside element and said elements being connected at their ends by transverse webs, said bricks abutting each

other at the ends of said inside webs and spaces being left between the ends of the outside webs, said bricks being united together by mortar over only the marginal bottom and top adjacent surfaces of the bricks where the marginal end surfaces of the bricks are spaced to form a mortar receiving recess.

4. A wall construction comprising a plurality of layers of individual bricks, each of said bricks being provided with three spaced vertical longitudinal stretcher elements, the outside elements being somewhat shorter than the inside element and said elements being connected at their ends by transverse webs, said bricks abutting each other at the ends of said inside webs and spaces being left between the ends of the outside webs, said bricks being united together by mortar over only the marginal bottom and top adjacent surfaces of the bricks where the marginal end surfaces of the bricks are spaced to form a mortar receiving recess, the intermediate end surfaces being provided with interlocking means.

5. A wall construction comprising a plurality of layers or courses of individual bricks, each of said bricks being provided with three spaced vertical longitudinal stretcher elements, the outside elements being somewhat shorter than the inside element and said elements being connected at their ends by transverse webs, said bricks abutting each other at the ends of said inside webs and spaces being left between the ends of the outside webs, said bricks being used in single depth in said wall construction, closely interfitting at the intermediate portions of said sides and receiving mortar at the recesses formed between the outside webs at the front and back of the wall.

6. In a wall construction having an angle of the type including runner bricks having longitudinal front, back and center webs and end webs connecting said front, back and center webs, said end webs carrying diagonally opposite keying elements; corner bricks having front, back and center vertical webs and transverse vertical webs at an angle to each other carrying correspondingly keyed surfaces at an angle to each other to cooperate with runner bricks extending toward said angle.

7. In a wall construction having an angle of the type including runner bricks having longitudinal front, back and center webs and end webs connecting said front, back and center webs, said end webs carrying diagonally opposite keying elements; corner bricks having front, back and center vertical webs and transverse vertical webs at an angle to each other carrying correspondingly keyed surfaces at an angle to each other to cooperate with runner bricks extending toward said angle, said angle being 90°.

8. In a wall construction, of the type including a plurality of runner bricks having vertical front, back and center longitudinal webs and vertical transverse end webs connecting said longitudinal webs, said end webs forming projections and grooves to interlock with adjacent bricks; corner bricks being also provided with front, back and center vertical webs and with transverse vertical webs having cooperating projections and grooves to interengage with the projections and grooves of said runner bricks.

9. A corner cavity brick comprising a brick molded in the form of five longitudinal stretcher web elements, two of which are parallel to each other and the other three of which are also parallel to each other and said parallel groups be-

ing arranged at right angles to each other, transverse webs connecting the ends of said stretcher web elements, said webs being provided with grooved and projecting portions to form a locking engaging means to cooperate with and form a close connection with bricks having complementary shaped portions and extending in directions at right angles to each other from said cavity corner brick.

10 10. A cavity brick comprising a brick molded in the form of three bent parallel spaced longitudinal vertical stretcher webs connected and spaced by two pairs only of intermediate transverse vertical integral webs located at the ends of the brick, said transverse webs carrying complementary shaped grooved and projecting portions to serve as keys in respect to adjacent bricks.

11. A wall construction comprising runner bricks extending at right angles consisting of an elongated rectangular construction and corner bricks of L-shape, one of said runner bricks being fitted against the outside face of one leg of the L and the other being fitted against the inside face of the other leg.

12. A wall construction comprising runner bricks extending at right angles consisting of an elongated rectangular construction and corner bricks of L-shape, one of said runner bricks being fitted against the outside face of one leg of the L and the other being fitted against the inside face of the other leg, said runner and L-bricks being provided with interengaging key and slot portions.

FRED HENRY HEDINGER.
